UNITED STATES PATENT OFFICE

ROBERT J. BOOTH, OF DANNEMORA, NEW YORK

COMBINATION GARMENT AND KIT

Application filed September 9, 1929. Serial No. 391,400.

The present invention relates to a combination garment and kit.

The primary object of the invention is to provide an article of this character so constructed that it can be used, when not employed as a garment, for carrying tools of various kinds.

A further object of the invention is to provide an article of this nature having its bib portion so formed that it will constitute a receptacle in which loose tools, or a tool chest or bag containing tools may be placed therein for convenience in transporting the same, the construction being such that upon removal of the tools, a complete overall garment is provided.

Another object of the invention is to provide an article of this kind which can be easily and quickly folded for carrying tools and readily unfolded for use as a garment.

With these and other objects in view, this invention resides in the novel features of construction, formation, combination and arrangement of parts to be hereinafter more fully described, claimed and illustrated in the accompanying drawings, in which:

Figure 1 is a perspective view showing the combination garment and kit folded to form a kit.

Figure 2 is a perspective view showing the kit opened.

Figure 3 is a front view of a pair of overalls formed when the combination garment and kit is unfolded.

Figure 4 is a rear view of the garment.

Figure 5 is a sectional view on the line 5—5 of Figure 4.

Figure 6 is a sectional view on the line 6—6 of Figure 3.

Referring to the drawings, 1 designates the legs and 2 the seat of the garment, said seat having shoulder straps 3 secured thereto and said straps having their free ends provided with loops 4.

The bib portion 5 of the garment comprises a strip 6 which constitutes a bottom 7, sides 8 and 9, and ends 10, the side 9 having a relatively wide flap 11 carried thereby while the ends 10 have narrow flaps 12. The flap 11 is provided with straps 13 adapted to en-

gage the buckles 14 carried by the side 8 when the garment is used for carrying tools, as clearly shown in Figure 1 of the drawings. A handle loop 15 is secured to the flap 11 in order that the garment can be conveniently carried when it is used for carrying tools. It will thus be noted that the bib section provides a receptacle when necessary.

The bottom 7 has buttons 16 which are engaged by the loops 4 when the garment is being used upon the person.

As shown in Figure 2, the bib portion is arranged in a position to provide a receptacle for receiving a chest or bag of tools or, if desired, the tools may be placed loosely within the receptacle.

When the workman reaches his place of employment the tools can be conveniently removed.

Before the tools are placed in the receptacle, the legs 1 are folded therein, after which the tools are placed in the receptacle and the flap 11 folded and the straps 13 engaged with the buckles 14, thus closing the receptacle and at which time the hand loop 15 is conveniently positioned. The flap 11 and flaps 12 are provided with coacting snap fasteners 17 to effectively close the receptacle.

When the workman desires to don the garment, the flap 11 is released and the tools removed, after which the legs are unfolded. The receptacle is then turned inside out and the sides 10 tucked in between the sides 8 and 9, there being coacting snap fasteners 18 carried by the sides for holding said sides in position. Thus, it will be noted that when the receptacle is turned inside out, a bib of double thickness is provided and at which time the buttons 16 are located for convenient engagement with the loops 4 of the straps 3. The flap 11 and straps 13 will be concealed and the garment can be worn with comfort. The garment is formed from suitable fabric and when used as a garment will have the appearance of a conventional type of overall.

Obviously, the tools can be loosely placed in the receptacle but it is preferable that

they be placed in a bag or chest so that they can be quickly removed and retained in proper relation for ready use.

The invention provides in compact form, 5 overalls, jumper, and kit, whereby the garment may be self-contained when reduced to the form of a package without requiring a wrapper, cord or other usual binder. The 10 construction prevents separation of the parts and insures a kit being readily and conveniently at hand for reception of the overalls, tools and sundry articles without liability of loss of the loose articles, or necessitating the wrapping and tying of the package.

15 What is claimed is:

A combination garment and kit comprising a bifurcated nether garment, the nether garment at the front thereof being provided with a relatively long extension and at the 20 back thereof with a pair of straps, the extension intermediate the ends thereof being provided with side flaps, the outer end of said extension and said flaps being adapted to be folded inwardly to provide a bib which 25 in combination with said nether garment provides overalls, the extension being provided with means for engagement by said straps for holding said bib in wearing position, and the extension and flaps being adapted to be folded and secured together to provide a kit.

In testimony whereof I affix my signature,
ROBERT J. BOOTH. [L.S.]
